UNITED STATES PATENT OFFICE.

JOHN T. COWLES, OF CHICAGO, ILLINOIS.

SHIP-RAISING MECHANISM.

1,258,197.

Specification of Letters Patent. Patented Mar. 5, 1918.

Application filed June 29, 1917. Serial No. 177,678.

To all whom it may concern:

Be it known that I, JOHN T. COWLES, a citizen of the United States, residing at Chicago, in the county of Cook and State of Illinois, have invented certain new and useful Improvements in Ship-Raising Mechanism, of which the following is a specification.

My invention relates to a mechanism for raising sunken ships, and the like, and has for its object the provision of simple and efficient means of the character mentioned adapted to be operable from the surface of water in which a ship is sunk and which is capable of raising such sunken ships.

Other objects will appear hereinafter.

An embodiment of my invention is indicated in the accompanying drawings forming a part of this specification, and in which—

Figure 1 is a side elevation of a piercing member or harpoon embodying my invention with the top portion broken away.

Fig. 2 is a side elevation of the same with central portions broken away and showing the device in engagement with a portion of a ship, or the like.

Fig. 3 is a section taken on line 3—3 of Fig. 1.

Fig. 4 is a section taken on line 4—4 of Fig. 2.

Fig. 5 is a side elevation of a pontoon mounted on the top portion of a piercing member embodying my invention.

Fig. 6 is an enlarged fragmental section of the top portion of my piercing member.

Fig. 7 is a section of the same taken on line 7—7 of Fig. 6.

Fig. 8 is a fragmental view of the top portion of my piercing member.

Fig. 9 is an enlarged fragmental section of the top portion of my piercing member showing a fragment of the pontoon attached thereto; and

Fig. 10 is an enlarged section of the lower portion of my piercing member.

Referring more particularly to the drawings, I provide a piercing member having its lower end 11 pointed and a portion 12 immediately above the pointed portion substantially cylindrical. Above the cylindrical portion 12 I provide a somewhat smaller portion 13, preferably cylindrical. In the lower part of portion 12 I provide a plurality of slots 14, in the present instance, four of such slots are shown. In each of the

slots 14 I provide a pivotal arm 15 pivoted as at 16 to the part 12. Each of the arms 15 are substantially alike, and a description of one will suffice for all. As shown particularly in Fig. 10, the members 15 are each provided with a point 17 adapted to engage a shoulder 18 in a slot 14, permitting the arm 15 to swing downwardly to a horizontal position. The arms 15 are held in the slots 14 by means of a ring 19. The ring 19 is provided with a number of prongs 20 which are adapted to be engaged by the portion of a vessel 21 which is pierced by the instrument. Upon the prongs 20 engaging the part of the vessel pierced, the ring 19 is moved upwardly on the part 12 until it slips off the tops of the arms 15, permitting the springs 22 to throw the arms 15 outwardly until gravity will move them to their horizontal positions shown in Figs. 2 and 10. Since the ring 19 is positioned near the tops of the arms 15, the instrument will pass into the ship part 21 before the arms 15 fall down to their horizontal position, therefore, upon attempting to raise the piercing instrument the arms 15 will catch on the inner side of the ship part 21 and lift on the latter. After the arms 15 have been free, the ring 19 ordinarily falls down to its full line position shown in Fig. 2.

The upper end of the portion 13 is slotted as at 23, (see Figs. 6 and 9). In the slot 23 I provide catches 24, pivoted as at 25 to the top of the part 13. These catches 24 are normally pressed away from each other by means of links 26 and a tension spring 27. The arrangement of said spring and links are clearly indicated in Figs. 6 and 9. In order to provide a means for lowering the piercing member through the water to a vessel to be raised, I provide a cable 28 which is secured to a locking member 29 having a T-shaped head 30 at its lower end. The member 29 and head 30 are formed of such sizes and shapes as will fit under the T-shaped heads 31 of the catches 24. When the catches 24 are moved toward each other to locking engagement with the head 30, it will be apparent that the cable 28 will be firmly attached to the piercing member and provide a means for lowering the latter to its desired position. In order to maintain the heads 31 in locking engagement with head 30 I preferably provide a retaining member, such as ring 32. The ring 32 is adapted to encircle the upper end of mem-

ber 13 and engage the remote edges of the heads 31, thereby holding the latter in locking position with head 30. The means for locking the cable 28 to the member is preferably covered with a shield 33 so that the mechanisms hereinafter described for driving the piercing member into a vessel will not interfere with said locking means. In the present form this shield comprises a cylindrical member slightly larger than the top portion 34 of part 13. It will be apparent that the outside diameter of the cylindrical member 33 is substantially the same as the diameter of part 13, so that an article can slip easily from one to the other. The upper end of member 33 is constricted as at 35 in order to facilitate guiding articles over the shield 33. The shield 33 is also provided with slots 36 in its lower end through which the lower ends 37 of the catches 24 are adapted to pass. The shield 33 is provided with cables 38 by means of which, when it is not desired to use the shield further, the latter can be withdrawn from the part 34 and taken up and out of the way. Resting on top of part 34 of portion 13 is a conical guiding member 39 adapted to facilitate guiding articles over the shield 33. Said guiding member 39 is preferably provided with slots 40 in which the cables 38 may pass to prevent articles catching on the connecting means between the cables 38 and the constricted portion 35 of said shield.

In the use of my device the parts are assembled as indicated in Fig. 2, with the exception that the arms 15 are in their positions indicated in Fig. 1. The device is then lowered to the sunken vessel by the cable 28 and when brought in contact with the vessel a hammering member 41 is placed on the cable and lowered until it rides on the portion 13 of the piercing member. The weight member 41 is provided with cables 42 for operating the same. It will be apparent that by raising the weight member 41 and dropping it against the shoulder 43 on the piercing member that the latter will be driven into the side of the vessel. After the member has been driven into the vessel and the arms 15 brought to their positions indicated in Fig. 2, the weight member 41 is brought up to the top of the water and taken off the cable. Next the shield 33 is brought up and taken off the cable. Then the pontoon 44, shown in Fig. 5, is placed around the cable. This may be done by removing bolts 45 and passing the ring-like parts 46 around the cable, and then replacing the bolts 45. The pontoons 44 are then caused to descend in the water on the cable 28 by means of placing sufficient weights, not shown, on them. Such weights, of course, must be drawn up again after the 65 pontoons have been placed in position on

the piercing member. The weights will cause the pontoon 44 to descend on cable 28 and slide over the guiding member 39 onto the portion 13 of the piercing member. In the bore of the top ring portion 46 of 70 the pontoon is a restricted portion 47 which has a bore of sufficient size to slide over the substantially cylindrical portion 48 of the lower end of guiding member 39 and engage the top of ring 32 and drag the latter 75 downwardly until it slips under the heads 31 of the catches 24. As soon as said spring slips downwardly off the heads 31, spring 27 moves the links 26 and forces the catches 24 from their positions indicated in Fig. 6 80 to that indicated in Fig. 9. This movement of the catches frees the head 30, and at the same time moves the heads 31 over the top of part 47 of the pontoon and locks said pontoon to the portion 13 of the piercing 85 member. The cable 28 and guiding member 39 may be then drawn up out of the water, leaving the pontoon securely fastened to the top of the piercing member and with no connection with the top of the water. In the 90 use of my device, I preferably use a sufficient number of them to cause the vessel to rise. It will be apparent that when a sufficient number of these devices are secured to a ship, the latter will be raised by the buoyancy of the pontoons 47, which are preferably air-filled. It will be apparent, however, that the weights mentioned above may be dispensed with, and when so desired, the pontoons 44 may be filled with water to 95 cause them to sink, and when locked on the portion 13 of the piercing member, such water may be pumped out and fill them with air, thereby permitting them to raise the vessel. 100

While I have illustrated and described the preferred form of my invention, I do not desire to be limited to the precise details set forth, but desire to avail myself of such variations and changes as come within 110 the scope of the appended claims. 105

I claim:

1. In combination, an elongated piercing member; a pontoon slidably mounted on said piercing member; and catches mounted in the upper portion of said piercing member engaging the pontoon and locking the latter on said piercing member. 115

2. In combination, an elongated piercing member; a cable; locking means detachably connecting the cable with the piercing member; a pontoon slidably mounted on the cable and adapted to slide onto the piercing member and engage the lock for disconnecting the cable from the piercing member. 120

3. In combination, an elongated piercing member; a pontoon slidably mounted on said piercing member; a cable; a locking member on the cable; catches mounted on the piercing member; means holding the 130

catches in engagement with the locking member; a pontoon slidably mounted on the cable and adapted to move onto the piercing member and disengage said means 5 from said catches and free the locking member.

4. In combination, an elongated piercing member; a pontoon slidably mounted on said piercing member; a cable; a locking 10 member on the cable; spring pressed catches mounted on the piercing member; means holding the catches in engagement with the locking member; a pontoon slidably mounted on the cable and adapted to move onto 15 the piercing member and disengage said means from said catches and free the locking member; and means on the catches for engaging the pontoon and locking the latter on said piercing member when said pontoon 20 is on said piercing member.

5. In combination, an elongated piercing member; a cable; locking means connecting the cable with said piercing member; a shield over the locking means; and a driving member slidably mounted on the cable adapted to pass over said shield and engage 25 the piercing member to drive the latter into an object.

6. In combination, an elongated piercing 30 member; and locking catches pivotally mounted in the upper portion of the piercing member adapted to rock toward each other and lock a member inserted therebetween and to rock apart and lock a member 35 passed over said piercing member.

7. In combination, an elongated piercing member; locking catches pivotally mounted in the upper portion of the piercing member adapted to rock toward each other and lock 40 a member inserted therebetween and to rock apart and lock a member passed over said piercing member; resilient means tending to hold said catches in one of their locking positions; and means for holding said 45 catches in their locking positions.

8. In combination, an elongated piercing member; locking catches pivotally mounted in the upper portion of the piercing member adapted to rock toward each other and lock 50 a member inserted therebetween and to rock apart and lock a member passed over said piercing member; resilient means tending to hold said catches in one of their locking positions; means for holding said catches in

their locking positions; and means for moving 55 said last mentioned means to inoperative position for freeing the catches to the influences of said resilient means.

9. In combination, an elongated piercing member; a pontoon; ring members on the 60 pontoon and slidably engaging the piercing member; and catches in the piercing member engaging one of said ring members and locking the pontoon to said piercing member.

10. In combination, an elongated piercing 65 member having a slot in its upper end; two catches spaced apart and pivoted in said slot; a locking member extending between said catches; a cable secured to said locking member; a spring connected with said 70 catches and tending to hold the latter apart; a ring encircling the top of the piercing member and holding the catches in locking engagement with said locking members; and means for moving said ring out of engagement with the catches.

11. In combination, an elongated piercing member having a slot in its upper end; two catches spaced apart and pivoted in said 80 slot; a locking member extending between said catches; a cable secured to said locking member; a spring connected with said catches and tending to hold the latter apart; a ring encircling the top of the piercing member and holding the catches in locking 85 engagement with said locking members; a pontoon slidably mounted on the cable and adapted to slide onto the piercing member; and means on the pontoon adapted to engage said ring and move the latter out of engagement with said catches.

12. In combination, an elongated piercing member; two catches pivoted in the piercing member; a spring connected with said catches tending to separate the latter; a 95 member engaging said catches and holding them against moving away from each other; a pontoon having ring members slidably mounted on the cable and adapted to slide over the piercing member; and a shoulder 100 on one of the ring members of the pontoon adapted to engage the member engaging said catches and disengage such member from said catches.

In testimony whereof I have signed my 105 name to this specification, on this 21st day of June A. D. 1917.

JOHN T. COWLES.
